UNITED STATES PATENT OFFICE.

HARRY F. ROACH, OF ST. LOUIS, MISSOURI.

RAIL-JOINT.

1,013,613.

Specification of Letters Patent.

Patented Jan. 2, 1912.

Application filed May 5, 1911. Serial No. 625,175.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

10 This invention relates to rail joints.

One object of the invention is to provide a rolled and forged rail-joint consisting of a girder that comprises a horizontally disposed rail-supporting portion which is so designed that reverse strains are practically eliminated and the load is transmitted through the center of the joint to the ties without making a fulcrum of the ties and without causing an excessive pumping up 20 and down of the ties due to the fulcruming, thereby distributing the load to the ties which support the joint without liability of displacing the ties or loosening the bed of the track.

25 Another object is to provide a rolled and forged rail-joint of girder construction in which a portion of the compression member extends alongside of the heads of the rails and serves as an additional wheel-supporting member after the running portion of the head of the rails has worn down to such an extent that it is desirable to have an additional wheel-supporting surface at the ends of the rails. And still another object 30 is to provide a rail-joint which is so designed that it requires fitting of the base flanges of the rails at only one point, namely, at the ends of the rails, the joint being so constructed that the end bolts can 40 be tightened without liability of kinking the rails.

Figure 1 of the drawings is a side elevational view of a rail-joint constructed in accordance with my invention, the girder being broken away so as to more clearly illustrate the portion of the joint on which the rails rest; Fig. 2 is a top plan view partly in horizontal section; Fig. 3 is an end elevational view of the joint showing one 50 of the rails in cross section; Fig. 4 is a vertical cross sectional view taken at the center of the joint; Fig. 5 is a diagrammatic view illustrating one way of forming the joint; Fig. 6 is a vertical cross sectional

view of an insulated joint constructed in accordance with my invention; Figs. 7 to 55 11, inclusive, are perspective views of the various insulating members which are interposed between the rails and the metallic parts of the joint; and Fig. 12 is a vertical 60 sectional view illustrating a slight modification of my invention, said view being taken adjacent one end of the joint.

As previously stated, the joint is preferably rolled and forged from a piece of metal 65 and consists of a girder A arranged at one side of the rails and provided with an integral horizontally disposed rail-supporting portion 1 that forms part of the tension member of the girder, said rail-supporting 70 portion being formed integral with a portion 2 that bears upon the top faces of the base flanges of the rails and projects downwardly alongside of the edges of the base flanges of the rails, as shown in Figs. 3 75 and 4.

The metal from which the joint is formed is the same as is generally used in the manufacture of rails and other railway track structures and while I have used the expression "rigid rail-supporting portion" in some of the claims, I do not wish to imply 80 that the rail-supporting portion of the joint is absolutely inflexible as I, of course, realize that the metal from which rails and similar 85 devices are formed has a certain degree of resiliency. I have used the term "rigid" in some of the claims merely for the purpose of emphasizing the difference between my joint and joints having rail-supporting portions formed from spring metal or metal 90 which is so resilient that it will deflect easily and thus act as a yielding cushion or support for the rails.

The compression element of the girder 95 consists of a member 3 that extends longitudinally of the web of the girder underneath the heads of the rails and a member 4 that extends alongside of the rails and bears against one of the side faces of the heads of 100 the rails. I prefer to provide the member 4 with a top face 5 which is inclined downwardly from the top face of the heads of the rails, as shown in Figs. 3 and 4, and whose end portions incline downwardly at 105 a greater angle than the intermediate portion thereof so as to form a substantially twisted surface of similar design to the

tread surface of the wheel-supporting member of the rail-joint shown in my prior United States Patent No. 954,649, dated April 12, 1910.

- 5 When the joint is used with new rails the top face or surface 5 of the member 4 will not act as a wheel-supporting surface because said top face 5 lies in a lower horizontal plane than the wheel-supporting surface 10 of the rails, but after the heads of the rails wear down the top face 5 of the member 4 comes into service and acts as a wheel-supporting surface. The object in providing the compression member 4 of the girder 15 with a twisted top face or wheel-supporting surface is to accommodate a double-flanged or guttered wheel and permit such a wheel to pass over the joint without receiving an excessive vertical shock or jar.
- 20 The horizontally disposed rail-supporting portion 1 of the joint is provided at approximately its center with a flat surface 6 of relatively great area on which the end portions of the base flanges of the rails rest, 25 and the ends of this rail-supporting portion 1 incline downwardly from the central flat face 6, as shown in Fig. 1, so that the rails will not normally rest on the end portions of the rail-supporting member 1. By forming the joint in this manner, namely, providing the rail-supporting member 1 with a flat surface of relatively great area on 30 which only the ends of the abutting rails rest, and having the remaining portions of said rail-supporting member 1 spaced away slightly from the base flanges of the rails, I practically eliminate reverse strains and 35 distribute the load to the ties on which the joint rests without making a fulcrum 40 of the ties and without causing a pumping up and down of the ties due to fulcruming. This is a very desirable feature in a rail-joint for it prevents the terminals or end portions of the rails from being tilted upwardly by a wheel approaching the joint and it also reduces the cost of maintenance 45 of the track for the load is transmitted to the ties in such a manner that the tendency of the ties to work loose is reduced to a 50 minimum.
- The area of the flat surface 6 at the center of the joint is determined by the load which the rail is intended to carry. Consequently, this surface 6 can be so proportioned that 55 it does not extend any farther in either direction from the center of the joint than is absolutely necessary, thereby making it possible to design the joint in such a manner that only the required supporting surface 60 is provided for the base flanges of the rails. And still another desirable feature of such a structure is that the rails cannot fulcrum on the joint when a load is passing over the same for there are no surfaces between the flat central portion 6 and the

ends of the joint upon which the base flanges of the rails can turn or fulcrum. I also prefer to provide the under side of the rail-supporting member 1 with flat surfaces 6^a which bear upon the ties, so as to prevent said member from cutting into the ties, the surfaces 6^a being parallel to the rail-supporting surface 6 of said member and also parallel to the base flanges of the rails when no load is on the rails.

The flange 2 or portion of the girder which bears upon the top faces of the base flanges of the rails holds the end portions of the rails firmly down upon the flat supporting surface 6 of the member 1 and thus 70 securely clamps the end portions of the rails in position and prevents them from rising upwardly off the flat supporting surface 6. While I prefer to have the flange 2 bear upon the rails throughout the length of the 80 joint, it is not absolutely necessary to design the joint in this manner for the essential thing is to have the flange 2 bear on the end portions of the rails so as to prevent upward movement of the ends of the rails. 85 I also prefer to form the depending portion 2^a of said member 2 in such a manner that there is no tendency for the rails to kink when the bolts at the ends of the joint are tightened, the girder being so designed that 90 the portion 2^a bears snugly against the edges of the base flanges of the rails at the ends of the joint, as shown in Fig. 3, but not at the center of the joint, as shown in Figs. 2 and 4. It is desirable to have a slight clearance between the portion 2^a and the edges of the base flanges of the rails at the center of the joint so as to take up wear but if the joint were not provided at its ends with some means for preventing the rails from 95 being drawn inwardly towards the vertical web of the girder the rails would kink when the end bolts were tightened. This same result can be accomplished in other ways as, for example, in the manner shown in Fig. 100 12 where the portion 20^a is parallel to the edges of the base flanges of the rails and spaced away slightly from said edges, and fillers 20^b are arranged between the rails and the web of the girder at the ends of the 105 joint so as to prevent the rails from being drawn inwardly toward the girder when the end bolts are tightened, the ends of the rails, of course, being clamped securely in position by the part 2 and the flat surface 6 which fit the base flanges of the rails snugly. The fillers 20^b are retained in position by 110 means of bolts, as shown in Fig. 12, and the openings in the fillers and in the vertical webs of the rails through which said bolts pass are made large enough to permit sufficient play of the bolts to prevent the bolts from interfering with the slight vertical deflection of the rails at the ends of the joint. A joint of the form shown in Fig. 1 or in 115 130

Fig. 12 permits the bolts to be tightened without kinking the rails, but still it is only necessary to have the joint fit the base flanges of the rails at one point, namely, at 5 the ends of the rails.

It is preferable to arrange a bar 7 along-side of the webs of the rails and connect said bar to the girder A by means of bolts 8 which pass through said parts and through 10 the webs of the rails. The member 3 which lies under the heads of the rails is preferably so designed that it does not bear against the under side of the heads of the rails at the center of the joint or at the ends of the joint, 15 as shown in Figs. 3 and 4, so as to permit the rails to deflect downwardly slightly when a load is imposed upon them and thus bring the base flanges of the rails gradually into engagement with the inclined surfaces 20 on the top face of the rail-supporting member 1 of the joint.

A rail-joint of the construction above-described holds the ends of the rails in position both vertically and horizontally without 25 performing the function of a "splice." Consequently, the strength and resiliency of the joint may be made the same as the strength and resiliency of the rails without tending to break the rails. Furthermore, 30 such a rail-joint eliminates battering of the receiving rail where traffic is in one direction because the center bearing of the joint on which the ends of the rails rest is higher than the rail-flange-engaging surfaces at the 35 ends of the joint, it is of sufficient area to provide a firm supporting surface for the rails, and the rails are held firmly down upon the same. Said center-supporting surface is not of great enough area, however, 40 to cause the rails to fulcrum thereon when a wheel reaches the end of the joint as would occur if the base flange supporting surface of the joint were cambered or curved.

45 By designing the joint in the manner above-described I am able to roll and forge it from a single piece of metal or form it entirely by a forging process. Consequently, I can produce at a low cost a rail- 50 joint which has all of the desirable features of the cast metal rail-joint shown in my prior patent above-referred to and also a few additional desirable features, such, for example, as the flat supporting surface of 55 relatively great area on which the end portions of the base flanges of the rails rest, and also the means for preventing the rails from kinking when the end bolts are tightened.

In Fig. 5 I have illustrated one way of 60 forming the joint, the reference characters B designating roller dies which are so arranged that they will produce a member A of the cross sectional shape shown in said figure. After said member has been removed from the roller dies the portion 1

which constitutes the rail-supporting member of the joint is bent into a horizontal position by suitable dies, not shown. The end portions of this member 1 are then bent downwardly or away from the intermediate 70 portion of said member 1, and the end portions of the parts 3 and 4 of the compression member of the girder are displaced or bent downwardly, as indicated by dotted lines in Fig. 4, so as to impart the proper 75 drop to the end portions of the part 3, the part 2^a of the flange-engaging portion 2 being shaped properly by means of dies so that its intermediate portion will be spaced away 80 from the side edges of the base flanges of the rails at the center of the joint.

A rail-joint of the construction above-described is admirably adapted for use as an insulated rail-joint, and in Figs. 6 to 11 I have shown the joint used in this manner. 85 Instead of using a sole plate between the base flanges of the rails and the rail-supporting member 1 of the joint and a separate end post between the ends of the rails, I prefer to use a pair of sole plates 9 formed of 90 insulating material and each provided at its inner end with an integral end post 10, both of which lie between the ends of the abutting rails, each sole plate being provided at one edge with an upwardly projecting flange 95 11 which extends alongside of the edge of the base flange of the rail that rests upon the sole plate. The member C which is interposed between the girder A and the rails, 100 is formed of insulating material and conforms to the shape of one side of a rail, said member being provided at its upper edge with a flange 12 which projects upwardly a slight distance above the top face 5 of the member 4 of the girder. The portion of the 105 member C which bears upon the top faces of the base flanges of the rails laps over the upturned flanges 11 on the sole plates and is provided with a depending flange 13 that lies between the upturned flanges 11 on the 110 sole plates and the part 2^a of the rail-joint. The insulating member D which is arranged between the bar 7 and the rails, conforms to the shape of the rails, and suitable washers 115 14 and sleeves 15 of insulating material are provided for insulating the bolts 8 and the nuts thereon from the metallic parts of the joint. I also prefer to arrange bushings 16 of insulating material in openings in the rail-supporting member 1 of the joint for 120 receiving the spikes or fastening devices that secure the joint to the ties, said bushings 16 also operating to prevent the sole plates from moving laterally.

An insulated rail-joint of the construction 125 above-described has a relatively large area of insulation, and as the joint is designed in such a manner that the pressure of the load is applied gradually to the rail-supporting member 1, the sole plates will not receive 130

sudden shocks or be hammered when the wheels pass over the joint.

Another desirable feature of such a construction is that rust and "findings," namely, small metal grindings from the brake-shoes, wheels and rails can not collect and form a bridge across the ends of the rails and thus produce a short circuit owing to the fact that the end posts are formed integral with the sole plates. Furthermore, there is sufficient space between the girder and the insulating member C to insure proper ventilation and drainage, and as the member C laps over the sole plates and terminates at the rail-supporting member 1 whose top face inclines downwardly from the intermediate portion thereof, ample provision is made for drainage. Consequently, a rail-joint of the character above-described increases the life of the insulating material and thus reduces the cost of maintenance of the joint.

Having thus described my invention, what I claim as new and desire to secure by Letters Patent is:

1. A rail-joint provided with a rigid rail-supporting member having a flat rail-bearing surface at approximately the center thereof, and two angularly-disposed flat rail-bearing surfaces which incline downwardly in opposite directions from said central flat surface.

2. A rail-joint consisting of a member of girder construction having a horizontally disposed rigid rail-supporting portion whose top face is flat at approximately the center and inclined downwardly toward the ends of said portion.

3. A rail-joint comprising a rigid horizontally disposed rail-supporting member whose top face is flat at the center and inclined downwardly toward the ends of said member, and means which bears upon the base flanges of the rails and holds them down upon the flat surface at the center of said member.

4. A rail-joint consisting of a girder having an upper member which extends alongside of the heads of the rails, and a rigid horizontally disposed rail-supporting portion whose top face is flat at approximately the center and inclined downwardly slightly toward the ends.

5. A rail-joint consisting of a girder having an upper member which extends alongside of the heads of the rails, and a horizontally disposed rail-supporting portion whose top face is flat at approximately the center and inclined downwardly slightly toward the ends of said portion, said upper member being provided with a wheel-tread surface which comes into service after the treads of the rails have worn down.

6. A rail-joint comprising a member having a bearing on which only the end por-

tions of the rails normally rest, thereby providing for a slight vertical deflection of the rails at the ends of the joint, said bearing extending the entire width of the base flanges of the rails, and means at the ends of the joint for preventing the rails from moving laterally at these points when the end bolts are tightened.

7. A rail-joint consisting of a horizontally disposed rail-supporting member provided adjacent one edge with an over-lapping part that extends over the base flanges of the rails, said part bearing on the top faces of said base flanges at the center of the joint and bearing against the side edges of said base flanges only at the ends of the joint.

8. A rail-joint consisting of a girder provided with an upper member that extends alongside of the heads of the rails, said member having a twisted wheel-tread surface which comes into service after the treads of the rails have worn down so as to carry a double-flanged or guttered wheel across the joint without an excessive vertical shock or jar, and a horizontally disposed rigid rail-supporting member at the lower edge of said girder whose top face is flat at approximately the center of said member and inclined downwardly toward the ends.

9. A rail-joint consisting of a forged or rolled girder provided at its upper edge with a member which extends alongside of the heads of the rails and at its lower edge with a horizontally disposed rigid rail-supporting portion having an area on which only the end portions of the base flanges of the rails normally rest.

10. A rigid rail-joint consisting of a forged or rolled girder having a portion which laps over the base flanges of the rails, and a horizontally disposed rail-supporting portion having an area on which only the end portions of the base flanges of the rails normally rest.

11. A rail-joint consisting of a forged or rolled girder having a compression member which acts as a wheel-supporting member after the treads of the rails have worn down, and a tension member which supports the base flanges of the rails, the intermediate portion of the top face of said tension member being higher than the end portions of said top face so as to provide for a slight deflection of the rails when a vertical load is imposed on the same.

12. A rail-joint consisting of a forged or rolled girder having an upper member extending alongside of the heads of the rails which is provided with a twisted top surface that acts as a wheel-tread after the treads of the rails have worn down, a horizontally disposed rigid rail-supporting portion at the lower edge of the girder whose top face is substantially flat at approximately the center and inclined downwardly

toward its ends, and means on said girder which bears upon the top faces of the base flanges of the rails.

13. A rail-joint provided with means for preventing vertical movement of the rails at the center of the joint, and means which prevents lateral movement of the rails at the ends of the joint but does not interfere with a slight vertical deflection of the rails at these points.

14. A rail-joint comprising means which firmly clamps the base flanges of the end portions of the rails and permits a slight vertical deflection of the rails at the ends of the joint and means for preventing lateral movement of the rails at the ends of the joint when the end bolts are tightened.

15. A rail-joint comprising a rigid rail-supporting member on which only the end portions of the rails normally rest, said member comprising means for permitting a slight vertical deflection of the rails at the ends of the joint, a member which bears upon the top face of the base flanges of the rails, and means at the ends of the joint for preventing lateral movement of the rails at these points when the end bolts of the joint are tightened.

16. A rail-joint comprising a girder having a rail-supporting portion whose top face is provided with a surface on which only the end portions of the rails normally rest, means coöoperating with the base flanges of the rails for preventing vertical movement of the end portions of the rails, and means which prevents lateral movement of the rails at the ends of the joint when the end bolts of the joint are tightened but does not interfere with a slight vertical deflection of the rails at these points.

17. A rail-joint comprising means for preventing both lateral and vertical movement of the end portions of the rails and means at the ends of the joint which prevents lateral movement of the rails but does not interfere with a slight vertical deflection of the rails at the ends of the joint.

18. A rail-joint having a rigid rail-supporting member which is provided with a bearing surface on which only the end portions of the rails normally rest, thereby providing for a slight vertical deflection of the rails intermediate their ends under load, and means which maintains the rails in alignment and prevents lateral movement

of the rails at the ends of the joint when the end bolts are tightened.

19. A rail-joint comprising a girder having a rigid rail-supporting member which is provided with a bearing surface on which only the end portions of the rails normally rest, and means at the ends of the girder for resisting lateral movement of the rails so as to prevent the rails from kinking when the end bolts of the joint are tightened.

20. A rail-joint comprising a girder having a rail-supporting member which permits the rails to deflect vertically slightly intermediate their ends under load, and a longitudinally extending member under the heads of the rails which does not interfere with the vertical deflection of the rails.

21. A rail-joint having a horizontally disposed rigid rail-supporting member whose top face is composed of a flat surface on which the rails normally rest, and inclined flat surfaces which are normally spaced away from the rails but which support the rails when a load is imposed upon the rails.

22. A rail-joint having a rigid rail-supporting member provided on its top face with three flat bearing planes two of which are angularly disposed with relation to the other, and on its bottom face with flat tie-engaging surfaces that are parallel to one of said bearing planes.

23. A rail-joint having a rail-supporting member whose top face has a flat rail-bearing surface and rail-bearing surfaces which incline downwardly therefrom, and tie-engaging surfaces on the bottom of said member that are parallel to the flat surface on the top face of said member.

24. A rail-joint consisting of a girder provided with a rail-supporting member whose top face is composed of a flat central plane and two inclined planes which form bearing surfaces for the base flanges of the rails, and a member on said girder which lies under the head of the rails and which permits the rails to deflect vertically at the ends of the joint.

In testimony whereof I hereunto affix my signature in the presence of two witnesses, this second day of May, 1911.

HARRY F. ROACH.
